UNITED STATES PATENT OFFICE.

LOUIS GYORFFY, OF ALLIANCE, OHIO.

ELEVATOR SAFETY DEVICE.

1,026,159.

Specification of Letters Patent. Patented May 14, 1912.

Application filed September 6, 1911. Serial No. 647,809.

To all whom it may concern:

Be it known that I, LOUIS GYORFFY, a subject of the King of Hungary, residing at Alliance, in the county of Stark and State of 5 Ohio, have invented certain new and useful Improvements in Elevator Safety Devices, of which the following is a specification, reference being had therein to the accompanying drawing.

10 This invention relates to an elevator safety device, and my invention aims to provide:—First, a device that will prevent the sudden descent of an elevator cage when the hoisting cables thereof break. Second, a 15 safety device consisting of comparatively few parts inexpensive to manufacture and easy to install. Third, a device that can be used in connection with various types of cable hoisted elevators. Fourth, a device that 20 will save lives and guard against the loss of property due to the falling of elevator cages.

The invention further aims to accomplish the above results by a combination of mechanical elements that will be hereinafter 25 specifically described and then claimed, and reference will now be had to the drawings, wherein:

Figure 1 is a front elevation of the elevator safety device, partly broken away and 30 partly in section, showing the device in an inactive position, Fig. 2 is a similar view of a portion of the elevator showing the safety device in an active position, Fig. 3 is a plan of the device, and Fig. 4 is a vertical 35 sectional view of the same.

The reference numerals 1 denote vertical oppositely disposed channel guides having the confronting faces thereof provided with racks or teeth 2 presenting horizontal shoulders 3. Slidably mounted between these 40 vertical guides is an elevator cage, comprising a bottom 4, walls 5 and transverse beams 6 arranged between the upper edges of the side walls of said cage. The beams 6 are arranged centrally of the top of the cage and 45 in parallelism, said beams having the confronting faces thereof, contiguous to the upper edges, connected by an integral web 7, thereby providing substantially an H-shaped beam. The web 7, intermediate the 50 ends thereof, is provided with two vertical openings 8 and movably arranged in these openings are vertical rods 9. The upper ends of the rods are formed integral with a 55 connecting head 10 having eyes 11 to which hoisting cables 12 are attached. The con-

necting head 10, at the upper ends of the rods 9, presents horizontal shoulders 13, for a purpose that will presently appear.

Arranged upon the lower ends of the rods 60 9 is a plate 14 which is retained upon said rods by cotter pins 15 or other fastening means. The plate 14 loosely fits in the lower part of the transverse beam and is guided therein by the beams 6 and the side walls of 65 the elevator cage.

Encircling the rods 9, between the plate 14 and the web 7, are coiled compression springs 16 and these springs are normally retained under tension during the operation 70 of the elevator cage.

Pivotedly connected to the upper ends of the rods 9 by pins 17 are the bifurcated inner ends 18 of locking arms 19, said arms having the outer ends thereof beveled, as 75 at 20 and normally resting upon the web 7. The locking arms 19 extend through straps 21 having the lower ends thereof bolted or otherwise secured, as at 22 to the outer sides of the beams 6, said straps being arranged at points intermediate the ends of the locking arms 19 for supporting the car from said arms.

In operation, the action of the safety device when the hoisting cables 12 break, is as 85 follows:—Immediately upon the connecting head 10 being released, the tension of the springs 16 is released and these springs lower the plate 14 and the rods 9 relatively to the web 7. The locking arms 19 are 90 therefore carried into engagement with the web 7, as shown in Fig. 2 of the drawings, this position of the locking arms causing the beveled ends 20 of said arms to protrude into the path of the teeth 2 and engage the 95 shoulders 3. As the beveled ends of the locking arms will be held by said shoulders and the lower ends of the rods 9 guided by the plate 14 between the beams 6, the descent of the elevator cage will allow the locking 100 arms to remain in a horizontal position to be engaged by the straps 21, which immediately prevent a further descent of the elevator cage. This action is instantaneous upon the hoisting cables 12 breaking, and with the 105 inner ends of the locking arms movably anchored, said arms are quickly thrown into an active position, whereby the shoulders 13 of the connecting head 10 will rest upon the inner ends of the locking arms, with the 110 outer ends of said arms in engagement with the shoulders 3 and in this manner support

the elevator cage until repairs can be made. The locking arms are maintained in a rigid horizontal position forming a truss of sufficient strength to support the elevator cage, 5 and after the hoisting cables have been repaired, said arms are quickly restored to their normal position ready again for instant use.

The safety device is made of strong and 10 durable metal and can be used in connection with freight or passenger elevators.

What I claim is:—

In an elevator safety device, the combination with vertical guides having the 15 confronting faces thereof provided with teeth, a cage slidably mounted between said guides, and hoisting cables adapted to raise and lower said cage, of transverse beams arranged in parallelism at the top of said 20 cage, a web connecting the confronting faces of said beams, vertical rods movably ar-

ranged in said web, a guide plate carried by the lower ends of said rods between said beams, coiled compression springs encircling said rods between said web and said plate, 25 a connecting head connecting said rods and said hoisting cables and providing horizontal shoulders, locking arms having the inner ends thereof pivotally connected to said rods adjacent to said shoulders and the outer ends 30 thereof beveled and adapted to engage the teeth of said guides, and straps carried by the outer sides of said beams and adapted to be engaged by said arms whereby the car will be supported from said straps. 35

In testimony whereof I affix my signature in the presence of two witnesses.

LOUIS GYORFFY.
